UNITED STATES PATENT OFFICE.

DAVID A. FRAMPTON AND GEORGE E. DENNISON, OF YOUNGSTOWN, OHIO.

RAIL JOINT.

Application filed November 10, 1924. Serial No. 748,832.

To all whom it may concern:

Be it known that we, DAVID A. FRAMPTON and GEORGE E. DENNISON, citizens of the United States of America, residing at Youngstown, in the county of Mahoning and State of Ohio, have invented certain new and useful Improvements in Rail Joints, of which the following is a specification.

This invention relates to rail joints. The object of this invention is to provide approved means for joining the adjacent ends of railway rails. The principal object is to provide a joint of this class, which will eliminate the necessity of using bolts which are ordinarily used to hold fish plates on both sides of the neck of the rails where joined.

A further object of this invention is to provide a pressed steel yoke, strong in construction, simple in manufacture and inexpensive.

A still further object is to provide non-boltable fish plates in conjunction with a tapered wedge having a channel edge.

With these and other objects in view, the invention consists in the novel arrangement and construction of parts, which will be hereinafter more fully explained.

In the accompanying drawing:—

Figure 1 is a perspective view of the rail joint completely assembled.

Figure 2 is a cross section taken on line 1—1 of Figure 1.

Figure 3 is a side elevation of portion 35 of a rail.

By referring to Figure 1, it will be seen that we have provided a device for securing the ends 1 of ordinary rails 2, so that the same may be held in proper relation to each other. In doing this, we have provided a yoke 3 which is made from a flat rectangular piece of iron or steel in which a desired inner portion of this flat rectangular iron or steel piece has been punched or sheared out.

This yoke 3 is shown in Figure 1, properly shaped by bending downwardly ends 4 at right angles to the central portion 5 of the yoke 3.

By referring to Figure 2, it will be seen that the downwardly turned ends 4 are provided with a recess 6 in which rest the bases of rails 2.

By referring to Figure 3, it will be seen that the neck 7 of the rail 2 is provided with an opening 8.

In assembling the device, the yoke 3, is slipped over the end of one of the rails and back beyond the end 1 of the rail 2. The other rail is now placed adjacent so that the ends 1 meet. The yoke 3 is now slipped out until the central portion of the yoke 3 is opposite the joining of the ends 1. Fish plates 9 and 10 are now placed in position in the order given. The fish plate 10 is provided with a projection 11 which fits into the opening 8. A tapered wedge 12 with a channeled edge 13 is now slipped in between the fish plate 10 and the edge 14 of the central portion 5. When the tapered wedge 12 is driven in the fish plate 9 is forced against an edge 15 of the central portion 5, thereby firmly gripping the neck 7 of the rails 2.

What we claim is:—

In a device of the class described, a yoke 75 formed of flat iron or steel having ends turned downwardly at right angles after desired inner portion has been cut out forming a seat for the bases of ordinary rails, two fish plates having outwardly extending 80 base flanges, a projection formed on one of said fish plates for the purpose of functioning with an opening in the end of the neck of a rail, a tapered wedge having a channeled edge, said wedge functioning between the 85 oppositely disposed edge of the central portion of the yoke and one of the fish plates, substantially as described for the purpose set forth.

In testimony whereof we affix our signatures.

DAVID A. FRAMPTON.
GEORGE E. DENNISON.
